UNITED STATES PATENT OFFICE

THURLOW E. McFALL, OF SPARTA, MICHIGAN

KNULED PISTON RING ARBOR

Application filed April 21, 1930. Serial No. 445,947.

This invention relates to an arbor for holding piston ring castings which are against movement in proper relation to each other and to cutting or splitting saws therefor, for the purpose of evenly dividing double width piston ring castings midway between their opposite flat sides. I have heretofore obtained Patent No. 1,749,147, issued March 4th, 1930, for a process of piston ring casting production, the essentials of which is the production of castings of double width, plus the necessary allowance for shrinkage and machining and a division of each double width ring casting into two equal parts, producing single ring castings of uniform character, with a complete absence of hard spots due to chilling, pressures and the like during the period that the molten iron is hardening.

It is a primary object and purpose of the present invention to provide a mechanism for the effective holding of a plurality of the ring castings side by side upon an arbor, and securing them against movement whereby each of the ring castings may be acted upon by a saw or equivalent cutter to thereby split each double width ring casting into two substantially like parts of the same width or whose variations are well within the limits of tolerance permitted. The invention is fully set forth in the following description, taken in connection with the accompanying drawings, in which,

Fig. 1 is an elevation illustrating the arbor of my invention holding a plurality of the ring castings and being acted upon by the saws.

Fig. 2 is an end elevation of the construction shown in Fig. 1.

Fig. 3 is a somewhat enlarged longitudinal vertical section through the arbor before its expansion to engage with the inner curved sides of the ring castings.

Fig. 4 is a view similar to Fig. 3 showing the arbor after its expansion to snugly engage against the inner sides of the ring casting.

Fig. 5 is a fragmentary enlarged section and elevation illustrating the manner in which the saws split the ring castings each

Figs. 6 and 7 are opposite end elevations of the arbor.

Fig. 8 is a fragmentary side elevation of the arbor, the parts at one end of the arbor being removed, and

Fig. 9 is a perspective view of a double width ring casting with a dotted line indication of how the same is divided or split into two like parts.

Like reference characters refer to like parts in the different figures of the drawings.

In the construction of the arbor, a shaft 1 of suitable length is provided which, at a plurality of spaced apart points, is formed with conical sections 2. Adjacent one end of the shaft a circular plate 3 is mounted, it being provided with a hub through which and the shaft a securing pin 4 may be passed to fix the plate to the shaft. A number of screws 5 thread through the plate 3 parallel to the axis of the shaft 1 and are adjustable to different positions, having the usual locking nuts for securing the screws in any position to which adjusted.

Around and lengthwise of the shaft 1 a series of arbor members 6 are located. Each is formed at its inner side with inwardly extending ribs 7 the inner edges of which are inclined to correspond with the inclinations of the conical sections 2 against which they bear. Preferably, four of the arbor members 6 will be used though the invention is in no sense limited to such particular number of arbor members.

It is evident that on longitudinal movement of the arbor members toward the plate 3 the same are moved radially outward and on longitudinal movement in the opposite direction they will move inward through the inner edges of the ribs 7 riding on the conical surfaces of the sections 2 of the shaft.

At the ends 8 of the arbor members nearest the plate 3, each is provided with a groove at its outer side and a coiled tension spring 9 or equivalent device seats in all of the grooves of all of said arbor members. The outside diameter of the grooved end portions 8 is greater than the diameter of the outer surfaces of the arbors, in this manner forming outwardly extending flanges the purpose of

which will hereafter be described.

The opposite ends of the arbor members 6 are reduced considerably in diameter and each is similarly grooved making grooved ends 10 in which a second coiled tension spring 11 is located. The coiled tension spring members 9 and 11 have the effect of automatically moving the arbor members to their collapsed position, causing the ribs 7 to ride inwardly on the conical sections 2 of the shaft when said arbor members are free for such movement.

The outer curved surface of each of the arbor members 6 is provided with a consecutive series of spaced apart narrow grooves 12, and the grooves in all of the arbor members are in alignment around the arbor. The projecting portions or tongues 13 between the grooves 12 are roughened at their outer surfaces. They may be ridged or file cut diagonally, as shown in Fig. 8, or knurled, or any other equivalent roughened surface which will engage the inner sides of the piston ring casting 14 located thereover may be used; or the outer sides of the arbors between the grooves 12 may carry rubber strips which serve as friction retaining members for the ring castings upon outward expansion of the arbor members 6 to bring the same against the inner sides of the ring castings. The ring castings 14 are readily placed over the smaller grooved ends 10 of the arbor member 6 and the first one placed thereover comes against the flanges provided by the grooved ends 8 as previously described.

In practice the double width ring castings 14, after they have been molded and cast, are ground upon their opposite opposed sides so that the ring casting has a certain width of face within tolerance limits of one-half thousandth inch whereby when a number of them are placed over the arbor members, the grooves 12 in said members are located midway between the parallel flat sides of the ring castings, there being a groove underneath each ring casting, as best shown in Figs. 3 and 4.

The outer end of the shaft 1 is exteriorly threaded as indicated at 1a and is provided with a keyway slot. A second circular plate 15 has a central hub 16 which allows the same to be slid over the end 1a of the shaft, and the hub has a key to follow the key-way slot to hold the plate from rotation, but permitting movement lengthwise of the shaft. A ring 17, provided with an annular flange or lip 18 at its inner side, is connected to the plate 15 at the inner side thereof by means of a number of studs or headed screws 19 which pass freely through openings in the plate 15 and are threaded into the ring. Between the inner side of the plate 15 and the ring 17 a plurality of coiled springs 20 are located and held, the tendency of which is to move the ring 17 from the plate 15 as far as permitted, or until the heads of the studs 19

come against the outer side of the plate 15. A nut 21 threads onto the outer end of the shaft 1a.

In placing a plurality of the ring castings 14 over the arbor, the nut 21 and the plate 15 with the attached ring 17 are removed, whereupon the springs 9 and 11 cause the arbor members to move inwardly to the position shown in Fig. 3 and a plurality of ring castings are readily placed over the arbor. The ring 17 and plate 15 are then placed over the end 1a of the arbor and the nut 21 threaded thereon against said plate 15. The plate is brought against the ends 10 of the arbor members moving them longitudinally and causing the inclined inner edges of the ribs 7 to ride outwardly on the inclined sections 2 of the shaft 1 until the opposite ends 8 of said arbor members abut against the ends of the screws 5.

This forces the arbor members outward so that the grooved, knurled or roughened outer surfaces 13 are pressed very firmly and snugly against the inner curved surfaces of the ring castings. In practice the ring castings are of the well known out-of-round form, made by the insertion of a gap piece or segment in a circular pattern split at one side to receive said segment. The surfaces of the arbor members 6 are arcs of cylinders whereby, when the arbor is expanded in the manner described, the ring castings are distorted from their out-of-round form to circular form, it being evident that the pressure of the arbor members 6 against the inner sides of the rings is necessarily heavy to produce such distortions. With the knurled or roughened outer surfaces of the arbor members 6 there is a very firm engagement of the ring castings with the arbor members, or twisting or binding when the cutting saws act upon the rings. The ring castings of course are held snugly against each other by the pressure of flange 18 of the spring actuated ring 17 before the arbor members are moved far enough outward to engage against the inner sides of the castings. Said pressure is a yielding pressure and in no way great enough to interfere with the sliding of the ring castings, at their contacting sides, by each other when the expanding arbor members 6 engage thereagainst; it being evident that the ring castings in the first instance are placed loosely over the collapsed arbor members and do not assume the smooth form that they have, indicated at their outer sides in Fig. 4, after the expansion of the arbor has been completed.

The extent of the outward or expanding movement of the arbor members 6 is gauged by the position of the screws 5. And it is apparent that the force with which the arbor, when fully expanded, engages against the inner sides of the ring castings may be readily controlled and changed by an adjustment of said screws.

An arbor loaded with ring castings 14 and fully expanded has such ring castings located in consecutive order and in engagement with each other side by side as shown in Fig. 1. 70

8. One end of the shaft 1 is adapted to detachably connect with the head stock 22 of a lathe or similar machine, and the other end with the tail stock spindle 23. A saw arbor shaft 24 has a plurality of saws 25 mounted thereon spaced apart from each other and held in parallel relation by spacing collars 26. This plurality or gang of saws is mounted so as to be fed to the ring castings at a side of the casting holding arbor preferably, and the saws rotating rapidly, and the arbor shaft also being turned, the saws readily split each ring casting 14 midway between its parallel or flat sides as indicated in dotted lines at 27, in Fig. 9, dividing each ring casting into two equal parts, each of which may be readily utilized thereafter for making a piston ring. The grooves 12 are in the planes of the saws so that said saws may be cut entirely through the castings. 80

15. It is to be understood that, so far as the invention herein is concerned, cutting tools of any suitable character, whether saws or otherwise may be used to split the ring castings midway between their sides, and no limitation on the invention should be made that the arbor must be used with a saw or gang of saws. Likewise, for a shorter length of arbor only one of the conical enlargements 2 will be used with a cooperating rib 7 on the 90 expanding arbor members. 95

20. The construction is one which has been produced after a considerable experiment and trial and after the production of various other arbors for attaining the same end as shown in prior pending applications for patent filed by me. Splitting the piston ring castings midway between their flat sides is readily accomplished in a very rapid and efficient manner. The invention is defined in 100 the appended claims and is to be considered within their scope. 110

I claim:

1. In a construction of the class described, a shaft, a plurality of arbor members around the shaft in spaced apart relation to each other and located lengthwise of the shaft, interengaging means between the shaft and inner sides of said arbor members for moving said members radially outward on longitudinal movement thereof in one direction along the shaft, means adjacent one end of said members for stopping the movement of the arbor members along the shaft, a plate slidably mounted on said shaft at the opposite end 115 of the arbor members, means for moving said plate along the shaft to engage with said opposite end of the arbor members and move them longitudinally, a ring movably mounted on said plate at the inner side thereof and springs between the plate and ring tending to 120
2. In a construction of the class described, a horizontal shaft, a plurality of arbor members located around and lengthwise of the shaft in spaced relation to each other, each of said arbor members at one end having an outwardly extending flange, interengaging means on the shaft and arbor members for moving said members radially outward on longitudinal movement thereof in one direction along the shaft, stop means mounted on the shaft against which one end of said arbor members engage to limit the longitudinal movement thereof, said arbor members being adapted to have a plurality of double width ring castings located thereover with the first ring casting placed thereon bearing against the flanges at said end of the arbor members, a plate slidably mounted on the shaft adjacent the opposite end of the arbor members and movable to engage therewith, a nut threaded onto said end of the shaft to move the plate into engagement with the ends of the arbor members, a ring around the shaft at the inner side of said plate, headed screws passing freely through said plate and threaded into said ring, and coiled compression springs between said plate and ring, substantially as and for the purposes described. 125
3. A construction containing the elements in combination defined in claim 2, said arbor members at their outer surfaces having a plurality of narrow grooves therein in spaced apart relation to each other and around the arbor members, the surfaces of said arbor members between said grooves having means to securely engage against the inner sides of ring castings located thereover and hold the ring castings against movement on outward expansion movement of the arbor members. 130
4. A construction containing the elements in combination defined in claim 2, said arbor members having a plurality of narrow grooves in spaced apart relation to each other at and around the outer surfaces of said members, said grooves being located with reference to piston ring castings placed over the arbor members such that each ring casting has a groove located thereunder substantially midway between the parallel flat sides of the ring casting. 135
5. A construction containing the elements in combination defined in claim 2, said arbor members having a plurality of spaced apart narrow grooves in and around the outer surfaces thereof, said grooves being located to piston ring castings placed over the arbor members such that each ring casting has a groove located under it substantially midway

between the parallel flat sides of the casting, and the surfaces of said arbor members between said grooves being roughened to securely engage with the inner sides of the ring castings when the arbor members are moved outwardly into engagement therewith.

6. In a construction of the class described, a horizontal shaft, a plurality of arbor members located around the shaft and lengthwise thereof, interengaging means between the shaft and inner sides of said arbor members for moving said members radially outward on longitudinal movement thereof in one direction along the shaft, means for moving said arbor members lengthwise of the shaft to expand the same outwardly, means to stop the longitudinal movement of said members, and means to yieldingly hold the piston ring castings against each other during and prior to the time of radial outward movement of said arbor members.

7. In a construction of the class described, a shaft having a plurality of spaced conical enlargements thereon, a plurality of arbor members located around the shaft lengthwise thereof and spaced from each other at their edges and provided at their inner sides with cooperating inclined sides to engage against

said conical enlargements on the shaft, each of said arbor members at one end having an outwardly extending flange to serve as stop means for the first of a plurality of piston ring castings placed over the arbor members, and means for moving the shaft and arbor members longitudinally with respect to each other to move said arbor members radially outward and thereby firmly engage the inner surfaces of said rings, said means also being adapted to press the first of said ring castings placed thereover against said flanges.

8. In a construction of the class described, a horizontal shaft, a plurality of arbor members located around the shaft and lengthwise thereof, interengaging means between the shaft and inner sides of said arbor members for moving said members radially outward on longitudinal movement thereof in one direction along the shaft, means for moving said arbor members lengthwise of the shaft to expand the same outwardly, means to stop the longitudinal movement of said members, and means to yieldingly hold the piston ring castings against each other during the time of radial outward movement of said arbor members.
